Kisselle
ATTORNEY.

UNITED STATES PATENT OFFICE

JOHN G. HICKMAN, OF DETROIT, MICHIGAN, ASSIGNOR TO TERNSTEDT MANUFACTURING COMPANY, OF DETROIT, MICHIGAN, A CORPORATION OF MICHIGAN

HANDLE ASSEMBLY

Application filed September 18, 1930. Serial No. 482,787.

This invention relates to a handle assembly and more particularly to a handle assembly for an automotive vehicle although it is understood that the invention may be applied to handle assemblies other than those used on an automotive vehicle. This invention is concerned with that type of handle assembly wherein a handle having a serrated opening therein for a serrated spindle is arranged to be fastened to the said spindle. It is an object of this invention to provide suitable means for piloting the said handle while it is being assembled to the spindle so that the serrations of the handle opening will properly engage between the serrations of the spindle.

It is an object of the invention to produce a raised shearing area adjacent the inner end of the opening in the handle, which shearing area is arranged to be sheared over as the handle is driven onto the spindle to insure a tight and rattle-proof fit of the handle on the spindle.

Another object of the invention is to provide spaced contact areas between the spindle and the opening therefor in the handle to prevent play between the handle and the spindle.

Since this invention relates to a handle assembly of the type wherein the handle is secured to a grooved spindle by a suitable U-shaped spring which is carried in a circumferential groove in the handle and has hooked ends which project through suitable openings into the spindle opening in the handle to engage the spindle in the groove to in turn retain the handle on the spindle, it is an object of the invention to facilitate the assembly of the handle to the spindle by providing suitable beveled surfaces over which the hooked ends of the spring slide during the assembly of the handle to the spindle.

In the drawings:

Fig. 1 is a sectional view showing the crank assembled to the spindle.

Fig. 2 is a section along the line 2—2 of Fig. 1.

Fig. 3 is a detail sectional view of the crank showing the spindle opening.

Fig. 4 is a detail view of the crank looking into the spindle opening.

Fig. 5 is a section along the line 5—5 of Fig. 3.

Figs. 6 and 7 are detail views of the spindle.

Referring more particularly to the drawings there is shown for purposes of description a window regulator handle assembly although it is understood that the invention may equally well be applied to a remote control and other handle assemblies. The handle assembly consists properly of the handle crank 1 provided in the outer end thereof with a suitable knob 2 that is rotatably mounted on the pin 3 which is fixed to the lower end of the crank. The term "crank" as used herein, includes any motion transmitting member adapted to rotate about an axis whether the motion or torque is transmitted from the member to the axis or vice versa. The crank is arranged to be secured to a spindle 4 and in non-rotatable relation therewith so that the driving torque may be conducted through the crank 1 to the spindle 4.

To this end the crank 1 is provided with an opening 5 having a plurality of serrations 6 which are parallel to each other and to the axis of the spindle opening 5 in the crank 1. The spindle 4 is likewise provided with a plurality of serrations 7 which are parallel to each other and to the axis of the spindle. The serrations 6 and 7 are arranged to nicely interfit so that each of the serrations 7 on the spindle 4 fits between each two consecutive serrations 6 of the opening 5 in the crank. In view of the commercial tolerances allowed in the fabrication of the crank and spindle, there is very apt to be a small play between the serrations which in turn gives a certain amount of lost motion between the spindle and the crank and more especially permits an in-and-out movement or axial play on the part of the handle. The invention contemplates the elimination of this movement between the spindle and the crank. To properly understand the means used for eliminating this lost play, the assembly of the spindle to the handle will be explained.

To this end the spindle 4 is provided with a circumferential groove 8. The hub 9 of the crank 1 is likewise provided with a circum-

ferential groove 10 which extends a little more than half way around the hub 9. The groove 10 is provided with openings 11 which extend inwardly toward the opening 5 in the 5 crank handle to connect the opening 5 with the groove 10. A suitable U-shaped spring 12 is seated in the opening 10 and has the bent end portions 13 which project through openings 11 into the opening 5. Hence, to 10 secure the crank 1 to the spindle 4, the opening 5 is aligned with the spindle 4 and then the crank is driven toward the spindle until the spring ends 13 snap into the groove 8 of the spindle 4 to fasten the crank to the spindle. 15

When the crank is being driven onto the spindle 4, it is very essential that the serrations 6 and 7 be properly positioned so that they will interfit. It is readily seen that if 20 a serration 7 be so positioned that it is not accurately aligned with the groove between, and formed by, each two consecutive serrations 6, then the serrations 6 will distort the serrations 7 and consequently there will be 25 a large amount of lost play between the crank 1 and the spindle 4. To eliminate this distortion of the one set of serrations by the other and to insure a proper interfit, it is proposed to project one of the serrations 6 30 outwardly beyond the others toward the mouth of the opening 5. This elongated serration may be referenced 14. The serration 14 may also be made slightly larger than the other serrations 6 so that as the crank is 35 driven onto the spindle the raised and enlarged serration 14 will be peened over to in turn cause a tighter interlocking between the crank and the spindle 4.

In assembling the crank to the spindle 4 40 the workman first aligns the opening 5 with the spindle 4 and pushes the crank onto the spindle 4 sufficiently to enable the projecting end 15 of the elongated serration 14 to engage between the serrations 7 of the spindle. 45 At this time the end 15 of the serration serves as a pilot and enables the workman to, in a sense, feel out the serrations 7 until the serration 15 is properly seated in a groove formed by two consecutive serrations 6. This 50 then assures the workman that the serrations 6 and 7 are properly positioned to insure a correct interfit. At this time the workman drives the crank fully onto the spindle till the spring ends 13 snap into the groove 8. 55 By so doing he shears the elongated serration 14 and causes a tight interfit of the spindle 4 in the opening 5.

Since in the assembly of the crank to the 60 spindle the spring ends 13 must ride over the outer portion of the spindle, it is proposed to circumferentially bevel the outer edge of the spindle as at 20, the serrations as at 21 and the portion between the groove 8 and the serrations 7 as at 22. This circumferential bevel

permits the spring ends 13 to easily slip over the various parts of the spindle 4.

To further insure a tight fit of the crank 1 on the spindle 4, it will be noted that the opening 5 in turn opens into a smaller co-axial 70 opening 23. This co-axial opening has projecting from its face the serrations 24. Any 75 number of serrations 24 may be used but preferably two serrations are used. These two serrations are 120° apart and likewise each is circumferentially 120° from the serration 14. Hence, as the crank is driven onto the spindle 4, the serrations 24 are engaged by the portion 32 of the spindle 4 beyond the serrations 7 and sheared over to tightly lock 80 this end portion of the spindle 4 in the opening 23. Hence, the shearing of the serrations 24 and 14 at points 120° apart insures a tight rattle-proof fit between the spindle 4 and the crank 1. The proper alignment of the 85 serrations 6 and 7 and the shearing of the serrations 14 in turn insures against any lost motion between the crank 1 and the spindle 4 in the direction of rotation of the crank because the deformed enlarged serration 14 90 wedges tightly between the two consecutive serrations 7 of the spindle between which it fits.

If desired, although it is not essential, because of the tight interfit between the spindle 4 and the crank 1, a coil spring 26 may be positioned between the bottom of the opening 23 in the end of the spindle 4. This serves as an anti-rattler in case an unusual or abnormal force should destroy the tight interfit of the 95 crank 1 and the spindle 4 as above explained. 100

In the machining of the spindle very often the frusto-conical portion 28 of the spindle 4 has a rough or sheared-edge 29. This sheared edge very often interferes with the snapping of the spring hooked ends 13 into the groove 8. Hence, to eliminate this defect it is proposed to remove this uneven or sheared edge 29 in any suitable manner to form a smooth, sharp edge as shown at 30 (Fig. 1). Hence, 105 the spring ends 13 are always able to snap into the groove 8. 110

It will also be noted that the spindle 4 contacts with the crank 1 at two spaced areas 31 and 32 respectively, that is, the hub portion 9 firmly contacts with the spindle 4 along the circumferential surface 31 and the outer end of the spindle 4 firmly contacts with the crank 1 in the opening 23 along the contact surface 32. This spaced relation of the contact surface 31 and 32 likewise prevents any play between the crank and the spindle in a plane perpendicular to the plane of rotation of the crank. 115

From the above description it is evident that there is here produced a handle assembly provided with spaced contact areas between the handle and the spindle and spaced shearing areas which insure a tight fit be- 120

tween the handle and the spindle and eliminate lost play in all directions.

When assembling the crank to the spindle 4, the crank engages the contact area 31 of the spindle in the outer portion of the opening 5 to properly axially align the opening 5 and spindle 4 before the spindle contact areas 32 and 31 engage the serrations 24 and 15 respectively to shear the same. The outer 10 peripheral edge of the spindle portion 22 also assists in shearing the enlarged serration 14.

I claim:

1. In a handle assembly or the like, the combination of, a crank having a serrated opening, a serrated spindle arranged to engage the crank in the said serrated opening, and pilot means on one of the said members serving to properly position the serrations on each of the said members during the assembly so that each serration on the one member will properly engage between each two consecutive serrations on the other member.

2. In a handle assembly or the like, the combination of, a crank with an opening therein having a plurality of parallel serrations, a spindle having a plurality of serrations arranged to engage the said crank in the said serrated opening, and pilot means on one of said members arranged to slidably engage between two consecutive serrations on the other member to guide the said members during the assembly of the one to the other so that each serration of the one is properly positioned between two consecutive serrations of the other member.

3. In a handle assembly or the like, the combination of, a crank with a serrated opening therein, a serrated spindle arranged to engage the said crank in the said serrated opening and combined pilot and deformable means for properly positioning the serrations of the one member with respect to the serrations of the other member during the assembly thereof and arranged to be deformed during the assembly thereof to tightly interengage the two members.

4. In a handle assembly or the like, the combination of, a crank having a serrated opening therein, a spindle having a plurality of serrations arranged to engage the crank in the said opening, at least one of the serrations on one of the above members projecting beyond the rest of the serrations on the said member to serve as a pilot during the assembly of the crank to the said spindle whereby each of the serrations on one of the said members is properly positioned in the groove formed by two consecutive serrations of the other member.

5. In a handle assembly or the like, the combination of a crank having a serrated opening therein, a spindle having a plurality of serrations arranged to engage the crank in the said opening, one of the said members

having a serration larger than the rest of the serrations and projecting beyond the same to serve as a pilot to properly position the serrations on the said spindle and in the opening in the said crank as the crank is being assembled to the said spindle, the said enlarged serration being deformed to tightly engage the spindle in the said opening.

6. In a handle assembly or the like, the combination of, a crank having an opening 70 therein, a spindle arranged to engage the crank in the said opening, one of said members having at least one raised surface arranged to be deformed when the said crank and spindle are assembled to tightly inter- 75 engage the crank and spindle.

7. In a handle assembly or the like, the combination of, a crank having a serrated opening therein, the serrations being spaced from the bottom of the said opening, a spindle arranged to engage the crank in the said serrated opening and having a serrated portion spaced from the end of the said spindle, and a raised surface arranged to be deformed between the portion of the opening between 80 the bottom and the serrations and the portion of the spindle between the end thereof and the serrations whereby the serrated spindle tightly interengages the crank in the 85 serrated opening.

8. In a handle assembly or the like, the combination of, a crank having a serrated opening therein, a serrated spindle arranged to engage the crank in the said opening, a raised deformable surface in front of and to the rear of the serrations on one of said members arranged to be deformed during the assembly 100 of the crank to the spindle to tightly interengage the said serrated spindle and crank.

In testimony whereof I affix my signature. 105
JOHN G. HICKMAN.
